UNITED STATES PATENT OFFICE

173,133

FRAME FOR RETAINING AND DISPLAYING MONOGRAMS OR THE LIKE

Richard Arbib, New York, N. Y., assignor to Signa-Craft, Inc., New York, N. Y., a corporation of New York

Application May 20, 1954, Serial No. 30,597

Term of patent 14 years

(Cl. D1—4)

To all whom it may concern:

Be it known that I, Richard Arbib, a citizen of the United States and a resident of the city, county, and State of New York, have invented a new, original, and ornamental Design for a Frame for Retaining and Displaying Monograms or the like, of which the following is a specification, reference being had to the accompanying drawings, forming a part thereof.

Fig. 1 is a top plan view.

Fig. 2 is an end view.

Fig. 3 is a side view showing the crown design.

Fig. 4 is a perspective view.

The dominant features of my design reside in the portions shown in full lines.

I claim:

The ornamental design for a frame for retaining and displaying monograms or the like, substantially as shown and described.
